DOOR LATCH MECHANISM

Otis O. Gould, Portland, Oreg., assignor of one-half to Wayne C. Harrigan, Seattle, Wash.

Application August 31, 1951, Serial No. 244,545

6 Claims. (Cl. 292—229)

1

This present invention is a door latch mechanism which consists of a rotary latch disc member that is normally actuated by an extending portion, of the same, engaging the door post or frame member causing the disc to be rotated by the movement of the door so that an open slot formed in the periphery of the disc will engage a fixed pin in the door enclosing frame in such a manner as to, in effect, cam the door into a well-seated final position. At this point a toothed, spring urged pawl engages ratchet teeth cut on the opposite side of the latch disc and thus holds the same in a secure engaged position.

In the past many latch mechanisms have been created, many of which well serve their intended purpose. In this present latch mechanism certain features of long proven design have been adapted in order that the specific result which it is desired to achieve could be attained with a mechanism that would give long periods of useful service. The present latch is especially usable where doors are to be held in closed position against repeated jarring and vibration. The automotive field is one involving a great deal of jar. On the other hand the use of a latch mechanism on boats and the like subjects it to a great deal of vibration. Probably the greatest hazard the latch mechanism faces is the indiscriminate use by various persons, few of whom will close a door carefully, but rather it is closed forcefully or slammed shut either in haste or in the hope of achieving a tighter closure. These various operating conditions therefore call for a latch mechanism so arranged with resilient means that it is very difficult to abuse the latch in use. These conditions have been considered fully in the production of this present latch mechanism and the details of structure that make it possible to secure these various conditions have produced a lock or latch of unusual simplicity which overcomes to a large degree the numerous faults and disadvantages which have been observed to date in locks or latches of this general type.

The principal object of this present invention is to provide a simple, foolproof and secure door latch.

A further object of this invention is to provide a door latch mechanism in which means are provided to insure that the various sequence of operations required in the opening and closing of the door can all be achieved under a wide range of operating conditions without damage or undue wear to the working parts of this latch.

A further object of this invention is to provide a latch mechanism which functions very

smoothly without the necessity of overcoming any heavy springs to the end that a closure can be made without jar which may be objectionable in the case of a vehicle or boat on one hand and which is very destructive to the mechanism of the latch on the other hand.

A further object of this invention is to provide a resiliently seated latch mechanism which will hold the various parts under compression so that there will be no objectionable vibration and especially no rattling of parts that would produce audible sounds.

A further object of this invention is to provide a latch mechanism and associated parts which make it possible to provide a fully weather-tight door closure.

A further object of this invention is to provide a latch mechanism composed of simple, rugged parts which are few in number and which act one with the other to provide an interlocking latch so that a very secure closure is obtained and one which will not become loosened due to vibration or shock.

Further objects, advantages and capabilities will be apparent from the description and disclosure in the drawings, or may be comprehended or are inherent in the device.

In the drawings:

Figure 1 is a horizontal sectional view through a door latch made after the teachings of my present invention;

Figure 2 is a fragmentary, perspective view showing certain of the parts employed in my latch;

Figure 3 is a sectional plan view showing certain parts employed with my latch in manually retracting the lock bolt or bar and taken in the same sense as Figure 1;

Figure 4 is a cross sectional view, in elevation, taken along the line 4—4 of Figure 3;

Figures 5, 6, 7, 8, 9 and 10 are horizontal cross sectional views showing in fragmentary, diagrammatic form the succession of positions assumed by various parts of my latch in various sequential steps in the unlocking of my mechanism, the locking bar is shown retracted.

Referring more particularly to the disclosure in the drawings, the numeral 12 designates the locking or latch disc forming an essential part of my present latch. This disc is disposed for partial revolution upon the fixed shaft 14. This disc is circular generally in form except for certain configurations on the periphery of the same.

Formed by cutting away a portion of the disc is the door jamb engaging lug 16. This mem-

ber comes into place during the closing action of my latch mechanism. Normally when the latch disc 12 is free for rotation it is revolved by spring 18 until the outwardly extending stop member 20 comes into abutment with the stop pin 21. This positions the straight front face of lug 16 accurately so that it will engage the door jamb, or a protective member thereupon, and causes the partial revolution of the latch disc so that it will engage the stationary latching pin 22 properly. The initial impact in closing is borne by lug 16 and the lug engaging edge of the jamb instead of the latching surfaces of pin 22 and notch 24 thereby protecting the latter members from considerable wear. A slotted notch 26 is formed in the periphery of the latch disc having a width to closely fit pin 22 and it is to be noted that the extended projection of the slotted notch would be tangent to a circle described about the center of shaft 14 and which circle would be of appreciably less diameter than the normal diameter of the latch disc. The angularity of this slot is critical in the functioning of the latch. This will be apparent particularly from a study of Figures 5 through 10. Notch 24 has considerable length in a tangential direction and pin 22 is held securely in both the positions shown in Figure 7 and Figure 5 due to the length of notch 24. It is common knowledge that often doors are not completely closed, as for instance car doors, and the usual latches often fail to secure the doors in the partially closed position. The present latching mechanism secures the door even if it is not completely closed, as shown in Figure 7. The various parts are so arranged that the notch in extending toward the pin 22 is directed partially in the direction the door moves in opening, i. e., Figures 5, 6 and 7, whereby any movement of the door toward opening more firmly latches it because of the inclined surface presented to pin 22 by the walls of notch 24.

On the diametrically opposite side of latch disc 12 from notch 24 is a plurality of ratchet teeth 30. These teeth are disposed angularly to give maximum holding means when the door 32 is closed fully upon the door jamb 34 after the showing of Figure 1, particularly. Adapted to engage teeth 30 is a sliding lock bar 36 having teeth 38 complementary to teeth 30 so that in the locking position, normally a plurality of teeth is engaged, both on the lock bar and on the teeth 30 of the latch disc. This is to provide the maximum security, to distribute wear over several surfaces, and to keep the height of the teeth to a minimum so that bar 36 need be retracted only a small amount to free the latch disc.

Lock bar 36 is held in position and guided by the housing 40 through which a cylindrical portion 42 passes and also a plurality of blocks or pins as 44 and 46. The depth of housing 40 as viewed in Figure 1 is relatively shallow so that vertical guidance is given also to the lock bar by the housing or spacing pieces secured thereto.

The sliding lock bar 36 is urged normally into engagement with the latch disc by a compression spring 50 preferably disposed upon the cylindrical portion of the lock bar and coming to rest against a washer or suitable abutment member 52. Member 52 should definitely be secured fixedly to the lock bar.

As this present latch will find use in almost all forms of doors, the retracting means for the lock bar and key locking means for the latch will of necessity have to be varied to meet these different requirements. In Figure 1 is illustrated a

push-button release having the horizontally reciprocating push button 54 which in turn bears upon bell crank 56. Bell crank 56 is urged usually in engagement with the push button by the coil spring 58 and may be secured conveniently to the pivot pin of the bell crank at 60. A short leg of the bell crank 56, or in some cases even a bifurcated leg, engages the face of abutment 52. With this arrangement, moderate pressure 10 on push button 54, aided as it is by the mechanical advantage provided in the unequal lengths of the bell crank 56, moves the lock bar a short distance to the left as viewed in Figure 1, thus releasing the latch disc 12. For use on most doors it is necessary to have interior release means also for bar 36 and this is achieved by the means shown in Figures 3 and 4 which usually are associated with the form shown in Figure 1, but for the sake of clarity of illustration have been shown with certain unrelated parts removed. For this purpose a preferably square revolvable shaft 62 is disposed horizontally immediately below lock bar 36 and has secured to it preferably two eccentric members as 64 and 66. As shaft 62 is revolved in either direction, abutment 52 and the associated lock bar will be moved to the left as viewed in Figures 1, 3 and 4, thus disengaging the ratchet teeth and freeing the latch disc.

30 Under most conditions of use, except possibly in residences or other buildings it is desirable to provide that the door be latched in a manner to prevent its vibrating or rattling, and it has been found in order to provide this characteristic that 35 a degree of resiliency must be imposed upon certain of the parts. It will be apparent it is believed that guide members 44 and 46 might be to a degree resilient. However the preferred form is to provide a resilient sealing member as 70 in the 40 form of a strip or gasket which may be secured to either the door 32 as shown in Figure 1, or in many cases it could be secured better to the door frame 34. As part of door 32, a covering member 72 should be provided to cover fully from both 45 view and damage the resilient strip 70. Such a strip is preferably formed of rubber or rubber substitute materials although any form of resilient window stripping is entirely satisfactory.

Method of operation

50 Figures 5 through 10 illustrate sequentially the various positions of the latch mechanism as a door bearing the same is being opened. Figure 5 shows the various parts, especially the door and 55 the door jamb, in the same position illustrated in Figure 1 excepting that the locking bar 36 has been moved to the left by means of push button 54, or by the rotation of shaft 62. As soon as the ratchet teeth 30 and 38 are disengaged, the first 60 action is for the resiliency of strip 70 to move the door outwardly a small amount as illustrated in Figure 6. This tends to withdraw the stationary pin 22 slightly from the bottom of slot 24 and the various parts are then free to move easily. 65 In Figure 7 manual effort has been applied to the door to move it more to its open position and this has caused a partial revolution of the latch disc 12 about its pivot pin 14. Successive positions of door 32 are shown in Figures 8 and 9. In 70 these various views, Figures 5 to 9 inclusive, the rotation of the latch disc is caused by the engagement of slot 24 with the fixed pin 22. As soon however as pin 22 has become disengaged from slot 26, torsion spring 18, illustrated in Figure 1, 75 takes control of the latch disc and revolves it.

counterclockwise, as viewed, until abutment 20 engages stop 21 thus arresting its further rotary movement. This position is illustrated in Figure 10 wherein it is noteworthy that ratchet teeth 30 are still fully within housing 40 and the cut away portion of the latch disc at 74 gives full clearance for the engaging surface of lug 16 and this lug is the only portion of the disc extending out beyond its housing 40 forming part of door 32. It is to be noted that the fixed pin 22 lies wholly within door jamb 34 which is relieved at 16 to provide ample space so that the latch disc can at the proper time fully engage this pin.

The closing of the door is a substantial reversal of the opening but it is desired to point out that lug 16 is positioned accurately by means of spring 18, and abutment 20, and stop 21, and will be so positioned on each opening of the door. This is important in that the engagement of lug 16 with the outside surface 18 of the door jamb starts the revolution of the latch disc as it initiates its engaging or latching sequence. It therefore follows that there must be maintained a distinct relationship between the distance from surface 18 to pin 22 and between the working surface of lug 16 and slot 24. This relationship as illustrated throughout the drawings, when properly established, will insure the certainty of the sequence of operations required. The door is usually closed at considerable speed and normally continues on and gives some compression to strip 70, and at the end of the inward movement of the door, spring 18 urges teeth 30 and 38 into engagement and the secure latching of the mechanism in its most advanced position is completed. This operation brings out the desirability of having teeth 30 and 38 small in size so that the last bit of slack can be captured and the door held in a position to retain compression on strip 70.

It is believed that it will be clearly apparent from the above description and the disclosure in the drawings that the invention comprehends a novel construction of a door latch mechanism.

Having thus disclosed the invention, I claim:

1. A door latch mechanism secured to one edge portion of a door and the adjacent jamb, comprising: a fixed vertical shaft secured to said door near one side edge; a horizontal latch disc rotatably mounted on said shaft; the surface of said jamb adjacent said disc having a recessed portion and there being a vertical latching pin positioned in said recessed portion; said disc having a slotted notch of a width closely fitting said pin in its periphery with the projected extension of the axis of the slotted notch extending tangentially to a circle of substantial size having its center at said shaft and smaller than said disc; said disc having a jamb engaging lug on its periphery, said jamb having a lug engaging edge positioned to engage said lug as said door moves toward a closed position, said lug striking said lug engaging edge to rotate said disc and directing said pin into said notch and then said pin acting against the walls of said notch further to rotate said disc as said door completes its closing action, said disc having a relieved portion between said lug and said notch to pass said lug engaging edge; spring means connected to said disc biasing it toward an unlocked position in which said lug is disposed to strike said lug engaging edge and stop means connected to said disc stopping said disc from rotation upon it reaching said unlocked position; said disc having a ratchet toothed portion on its edge opposite said notch; a horizontal lock bar slidably mounted in said door to move toward and away from said disc, said bar having a toothed end directed toward said disc to engage said toothed portion thereof to lock said disc in locked position with said pin in said notch; said slotted notch having considerable length in its tangential extension and said toothed portion of said disc having considerable length whereby the toothed end of said lock bar will fixedly secure said disc even when the door is only partially closed; spring means connected to said lock bar and biasing said bar toward said disc; and manually operable means for moving said lock bar away from said disc to unlock the same.

5 a ratchet toothed end directed toward said disc to engage said toothed portion thereof to lock said disc in locked position with said pin in said notch; said slotted notch having considerable length in its tangential extension and said toothed portion of said disc having considerable length whereby the toothed end of said lock bar will fixedly secure said disc even when the door is only partially closed; spring means 10 connected to said lock bar and biasing said bar toward said disc; and manually operable means for moving said lock bar away from said disc to unlock the same.

2. The subject matter of claim 1 in which said 15 manually operable means includes a collar on said lock bar, a bell crank pivotally mounted in said door and having one end positioned to engage said collar, and a push button, positioned on the face of said door toward which the door 20 opens, engaging the other end of said bell crank.

3. A door latch mechanism secured to one edge portion of a door and the adjacent jamb, comprising: a vertical shaft secured to said door near one side edge; a horizontal latch disc rotatably 25 mounted on said shaft; the surface of said jamb adjacent said disc having a recessed portion and there being a vertical latching pin positioned in said recessed portion; said disc having a slotted notch of a width closely fitting said pin in its 30 periphery with the projected extension of the axis of the slotted notch extending tangentially to a circle of substantial size having its center at said shaft and smaller than said disc; said disc having a jamb engaging lug on its periphery, said 35 jamb having a lug engaging edge positioned to engage said lug as said door moves toward a closed position, said lug striking said lug engaging edge to rotate said disc and directing said pin into said notch and then said pin acting 40 against the walls of said notch further to rotate said disc as said door completes its closing action, said disc having a relieved portion between said lug and said notch to pass said lug engaging edge; spring means connected to said disc biasing 45 it toward an unlocked position in which said lug is disposed to strike said lug engaging edge and stop means connected to said disc stopping said disc from rotation upon it reaching said unlocked position; said disc having a toothed portion on its edge opposite said notch; a horizontal lock bar 50 slidably mounted in said door to move toward and away from said disc, said bar having a toothed end directed toward said disc to engage said toothed portion thereof to lock said disc in locked position with said pin in said notch; said slotted 55 notch having considerable length in its tangential extension and said toothed portion of said disc having considerable length whereby the toothed end of said lock bar will fixedly secure said disc even when the door is only partially closed; said 60 shaft, disc, pin and notch being so positioned that said notch, as it extends toward said pin, extends partially in the direction the door moves in opening, in the various positions of said notch in which said toothed portion of said disc is in position to be engaged by said toothed end of said lock bar; spring means connected to said lock bar and biasing said bar toward said disc; and manually operable means for moving said lock 65 bar away from said disc to unlock the same.

4. A door latch mechanism secured to one edge portion of a door and the adjacent jamb, comprising: a shaft secured to said door near one edge and parallel thereto; a latch disc rotatably mounted on said shaft; a latching pin positioned 70 on said jamb adjacent said disc and disposed

parallel to said shaft; said disc having a slotted notch of a width closely fitting said pin in its periphery with the projected extension of the axis of the slotted notch extending tangentially to a circle of substantial size having its center at said shaft and smaller than said disc; said disc having a jamb engaging lug on its periphery, lug engaging means on said jamb to engage said lug as said door moves toward a closed position, said lug striking said lug engaging edge to rotate said disc and directing said pin into said notch and then said pin acting against the walls of said notch further to rotate said disc as said door completes its closing action, said disc having a relieved portion between said lug and said notch to pass said lug engaging means; spring means connected to said disc biasing it toward an unlocked position in which said lug is disposed to strike said lug engaging means and stop means connected to said disc stopping said disc from rotation upon it reaching said unlocked position; said disc having a toothed portion on its edge opposite said notch; a lock bar slidably mounted in said door to move toward and away from said disc, said bar having a toothed end directed toward said disc to engage said toothed portion thereof to lock said disc in locked position with said pin in said notch; said slotted notch having considerable length in its tangential extension and said toothed portion of said disc having considerable length whereby the toothed end of said lock bar will fixedly secure said disc even when the door is only partially closed; spring means connected to said lock bar and biasing said bar toward said disc; and manually operable means for moving said lock bar away from said disc to unlock the same.

5. A door latch mechanism secured to one edge portion of a door and the adjacent jamb, comprising: a fixed vertical shaft secured to said door near one side edge; a horizontal latch disc rotatably mounted on said shaft; a vertical latching pin positioned on said jamb adjacent said disc; said disc having a slotted notch of a width closely fitting said pin in its periphery with the projected extension of the axis of the slotted notch extending tangentially to a circle of substantial size having its center at said shaft and smaller than said disc; said disc having a jamb engaging lug on its periphery, said jamb having a lug engaging edge positioned to engage said lug as said door moves toward a closed position, said lug striking said lug engaging edge to rotate said disc and directing said pin into said notch and then said pin acting against the walls of said notch further to rotate said disc as said door completes its closing action, said disc having a relieved portion between said lug and said notch to pass said lug engaging edge; spring means connected to said disc biasing it towards an unlocked position in which said lug is disposed to strike said lug engaging edge and stop means connected to said disc stopping said disc from rotation upon its reaching said unlocked position; said disc having a toothed portion on its edge opposite said notch; a horizontal lock bar slidably mounted in said door to move toward and away from said disc, said bar having a toothed end directed toward said disc to engage said toothed portion thereof to lock said disc in locked position with said pin in said notch; said slotted notch having considerable length in its tangential extension and said toothed portion of said disc having considerable length whereby the toothed end of said lock bar will fixedly secure said disc even when the door is only partially closed; said shaft, disc, pin and notch being so positioned that said notch, as it extends towards said pin, extends partially in the direction the door moves in opening, in the various positions of said notch in which said toothed portion of said disc is in position to be engaged by said toothed end of said lock bar; and spring means connected to said lock bar and biasing said bar towards said disc.

said disc in locked position with said pin in said notch; said slotted notch having considerable length in its tangential extension and said ratchet toothed portion of said disc having considerable length whereby the toothed end of said lock bar will fixedly secure said disc even when the door is only partially closed; spring means connected to said lock bar and biasing said bar towards said disc; and manually operable means for moving said lock bar away from said disc to unlock the same.

6. A door latch mechanism secured to one edge portion of a door and the adjacent jamb, comprising: a vertical shaft secured to said door near one side edge; a horizontal latch disc rotatably mounted on said shaft; the surface of said jamb adjacent said disc having a recessed portion and there being a vertical latching pin positioned in said recessed portion; said disc having a slotted notch of a width closely fitting said pin in its periphery with the projected extension of the axis of the slotted notch extending tangentially to a circle of substantial size having its center at said shaft and smaller than said disc; said disc having a jamb engaging lug on its periphery, said jamb having a lug engaging edge positioned to engage said lug as said door moves toward a closed position, said lug striking said lug engaging edge to rotate said disc and directing said pin into said notch and then said pin acting against the walls of said notch further to rotate said disc as said door completes its closing action, said disc having a relieved portion between said lug and said notch to pass said lug engaging edge; spring means connected to said disc biasing it towards an unlocked position in which said lug is disposed to strike said lug engaging edge and stop means connected to said disc stopping said disc from rotation upon its reaching said unlocked position; said disc having a toothed portion on its edge opposite said notch; a horizontal lock bar slidably mounted in said door to move toward and away from said disc, said bar having a toothed end directed toward said disc to engage said toothed portion thereof to lock said disc in locked position with said pin in said notch; said slotted notch having considerable length in its tangential extension and said toothed portion of said disc having considerable length whereby the toothed end of said lock bar will fixedly secure said disc even when the door is only partially closed; said shaft, disc, pin and notch being so positioned that said notch, as it extends towards said pin, extends partially in the direction the door moves in opening, in the various positions of said notch in which said toothed portion of said disc is in position to be engaged by said toothed end of said lock bar; and spring means connected to said lock bar and biasing said bar towards said disc.
